UNITED STATES PATENT OFFICE.

MORRIS GOLDBERG, OF BROOKLYN, NEW YORK.

ATTACHMENT FOR NECKSCARFS.

1,422,758.

Specification of Letters Patent. Patented July 11, 1922.

Application filed November 6, 1918. Serial No. 261,381.

To all whom it may concern:

Be it known that I, MORRIS GOLDBERG, a citizen of the United States, residing at Brooklyn, in the county of Kings and State of New York, have invented new and useful Improvements in Attachments for Neck-scarfs, of which the following is a specification.

This invention relates to attachments for neck scarfs and has for its primary object the provision of a device of this character which will include a neck encircling band or tape adapted to be so connected with a previously knotted and tied scarf as to render the same applicable to the collar at any time without the necessity of re-tying the same after each use and thereby minimize wear and tear thereon while simplifying and expediting an adjustment of the scarf to or removal thereof from the collar.

Another object of the invention is to provide an attachment of the specified type which will be adjustable to ordinary forms of scarfs without requiring changes in the construction thereof.

A still further object of the invention is to provide a scarf attachment which will consist of an adjustable elastic tape adapted for connection with the scarf respectively at the opposite sides of the knot, the elasticity of the tape serving to always maintain the knot of the tie in proper position with respect to the open ends of the collar.

Figure 1 is a front view of a scarf showing my improved attachment applied thereto.

Figure 2 is a rear view of the scarf.

In carrying the invention into practice, use can be made of any four-in-hand scarf such as the one shown at 5 and in practice the scarf is folded from a point approximately at the center of the neck band thereof so as to form a loop 7 at one side of the knot 6. An oval shaped loop member 7' is associated with the loop 7 of the tie and is adapted to act as a means for connecting the band 8 to said loop 7 as shown in Figure 1. The band 8 is preferably formed of elastic tape and it is folded upon itself at one end to produce an adjustable loop 9, the bight

of which is associated with the loop member 7'. The loop portion 9 of the elastic band or tape 8 is formed by extending one of the leads of the tape through an adjusting and retaining member 10. In this manner it will be observed that any desired adjustment of the band or tape can be secured to properly cause the same to fit the neck of the wearer.

The free end of the tape is provided with a hook 11. At the rear side of the knot 6, of the scarf is a detachable pin 12 which is designed to be engaged by the hook 11 when the scarf is adjusted to the collar. Under the inherent quality of the tape the knot will be uniformly held between the meeting ends of the collar. The tape 8 through the manner of connecting the same with the scarf is never visible when in use upon the collar. The design of the structure is such that the scarf can be tied to the form desired for use and the extension 7 permanently arranged at one side thereof with my improved attachment operatively applied thereto as described. This entirely eliminates the necessity of retying the scarf after each use thereof and consequently minimizes the wear and tear thereon while greatly facilitating the application of the scarf to or removal of the same from the collar.

What is claimed as new is:

1. In combination, a tie folded upon itself and knotted to provide a knot and a loop extending from one side of the knot, a tape having one end secured to the loop and means including a removable member secured to the knot for detachable connection with the opposite end of the tape.

2. In combination, a tie folded upon itself and knotted to provide a knot and a loop extending from one side of the knot, a tape having one end connected to the loop, a hook carried by the opposite end of the tape and a loop-shaped pin removably engaged with the knot for connection with the hook.

In testimony whereof I have affixed my signature.

MORRIS GOLDBERG.
